United States Patent Office

Des. 182,775
Patented May 13, 1958

182,775

SEA FOOD SHELL DISH OR SIMILAR ARTICLE

Harry A. Tomarin, Cincinnati, Ohio

Application February 28, 1957, Serial No. 45,027

Term of patent 14 years

(Cl. D44—15)

Fig. 1 is a bottom plan view of a sea food shell dish or similar article;

Fig. 2 is a top plan view;

Fig. 3 is a front elevational view;

Fig. 4 is a left end elevational view; and

Fig. 5 is a cross-sectional view on line 5—5 of Fig. 1.

I claim:

The ornamental design for a sea food shell dish or similar article, as shown.
